Attn: J. Berg.*

UNITED STATES PATENT OFFICE.

JOHN BERG, OF CHICAGO, ILLINOIS.

DESIGN FOR A CIGAR-LIGHTER.

44,995.

Specification for Design.

Patented Dec. 9, 1913.

Application filed September 19, 1913. Serial No. 790,797. Term of patent 14 years.

To all whom it may concern:

Be it known that I, JOHN BERG, a citizen of the United States, residing at Chicago, in the county of Cook and State of Illinois, have invented a new, original, and ornamental Design for a Cigar-Lighter, of which the following is a specification, reference being had to the accompanying drawing, forming a part hereof.

The drawing shows a perspective view of said design.

I claim:

The ornamental design for a cigar-lighter, as shown and described.

JOHN BERG.

In presence of—

A. J. FLOYD,

O. C. AVISUS.
